COMBINED MIRROR AND LAMP

Anthony Brozyna, Irvington, N. J.

Application February 16, 1949, Serial No. 898

Term of patent 14 years

(Cl. D86—10)

To all whom it may concern:

Be it known that I, Anthony Brozyna, a citizen of the United States, residing in Irvington, Essex County, New Jersey, have invented a new, original, and ornamental Design for a Combined Mirror and Lamp, of which the following is a specification, reference being had to the accompanying drawing, forming a part thereof.

Fig. 1 is a perspective view of a combined mirror and lamp embodying my new design in one position thereof, and

Fig. 2 is another perspective view of the combined mirror and lamp, with the parts thereof shown folded to a different position.

I claim:

The ornamental design for a combined mirror and lamp, as shown.

ANTHONY BROZYNA.
